PLLC(57) **CLAIM**

The ornamental design for a motorcycle luggage rack, as shown and described.

DESCRIPTION

FIG. 1 is a perspective view of the motorcycle luggage rack. FIG. 2 is a rear elevation view thereof.

FIG. 3 is a front elevation view thereof.

FIG. 4 is a left side view thereof.

FIG. 5 is a right side view thereof.

FIG. 6 is a top side view thereof; and,

FIG. 7 is a bottom side view thereof.

The top surface features, bottom surface, and mounting legs of the motorcycle luggage rack shown in broken lines form no part of the claimed design.
